UNITED STATES PATENT OFFICE.

HARRY P. GUILLO, OF REVERE, MASSACHUSETTS.

GRIPPER MECHANISM FOR CYLINDER-PRESSES.

979,845.

Specification of Letters Patent. Patented Dec. 27, 1910.

Application filed June 16, 1910. Serial No. 567,175.

To all whom it may concern:

Be it known that I, HARRY P. GUILLO, of Revere, in the county of Suffolk and State of Massachusetts, a citizen of the United States, have invented an Improved Gripper Mechanism for Cylinder-Presses, of which the following is a specification.

My invention relates particularly to the means whereby pressure is applied to the 10 grippers to cause them to hold the paper firmly against the impression cylinder and also to the means whereby they are caused to engage and release the paper.

My invention will be understood by reference to the drawings in which—

Figure 1 is an end view of an impression cylinder to which mechanism is attached embodying my invention. Fig. 2 shows the other end of the same cylinder together with 20 mechanism embodying my invention in another form as will be explained below, and Fig. 3 is a front view of the impression cylinder showing the gripper-operating mechanism in elevation—a portion of the 25 central portion of the cylinder being omitted. Fig. 4 is a perspective view of the tumbler lever, and Fig. 5 is a perspective view of the spring abutment.

In the drawings A is the impression cylinder which is mounted on trunnions A¹ 30 in the frame A² of the press and is rotated in any convenient way. It may be of any length and coöperate with the feed and other mechanism as usual. It is provided with 35 a gap A³ of proper character to receive the shaft B and grippers C as described below. The shaft B is mounted in the end or bearing walls of the cylinder and, when the cylinder is of sufficient length to require it, 40 in intermediate bearings. This shaft carries the grippers C which depend in number upon the length of the cylinder. They and the shaft and its bearings are of the usual character and need not be especially described. They coöperate in the usual manner with front gauges C¹, a feed board C² 45 and strippers C³ of any convenient form.

My improvement relates to the control of the shaft B which causes the grippers to 50 close upon the sheet and to open to release the sheet. Where the cylinder is short, the gripper-operating mechanism need be located at one end only. Where the cylinder is long there is danger that the torsion of 55 the shaft will affect the accurate operation of the grippers and hence the desirability

of the use of mechanism at each end of the shaft to prevent this torsion.

As shown in Fig. 1, there is mounted on one end of the shaft B a tumbler lever D (see Fig. 4) which comprises a casting having a hub d containing a socket by means of which it is attached to the shaft B by a pin or otherwise to turn it. On its opposite side it has a groove d¹ open at each end to engage the tumbler stud g or g¹ by which as the cylinder rotates the tumbler lever will be turned to turn the shaft and lift the grippers as below described. The tumbler lever also has a cam surface d² and an arm d³ to which a spring is connected for holding the grippers in operative or disengaged position.

The spring above referred to is marked E and is carried on a rod e one end of which has an enlargement by which it is pivotally attached to the arm d³, the said enlargement having a shoulder e². The other end of the rod slides in a block e³ having trunnions e⁴ which set into bearings in one end of a yoke lever F which is pivoted at F¹ to the cylinder A, thus securing a rocking bearing for that end of the rod e. One end of the spring E bears against the shoulder e² and the other against the block e³, the spring being held under considerable compression. The farther end of the yoke lever F carries a cam roll f which rides on the cam surface d². It is held against this cam surface by the spring E. The important 90 novelty and value of this construction as it seems to me is the fact that the spring while it is always under compression between the shoulder e² and one end of the yoke lever F sufficient to give the grippers tight hold on the paper never materially changes its stress. This is because of the movements of the yoke lever F which turns freely on its pivot F¹ and acts as a floating abutment to the spring, the cam surface d² being shaped 95 to allow for the necessary movements of the yoke lever at those moments when particular stress is brought to bear upon the spring. Thus the grippers will always be under heavy tension and at the same time 100 during the releasing movement described below movements of the tumbler which might otherwise increase the stress on the spring will be compensated for by the yielding of the yoke lever the amount of which 110 is controlled by the cam surface.

The only movement given to the tumbler

lever is that which is necessary to move the grippers into and out of engaging relation with the paper and this is accomplished by means of tumbler studs mounted in the frame in the usual way. The portion of the frame A² shown in Fig. 3 has in it two studs g, g¹ each of which is connected to a lever the end of which (g², g³) is shown in the drawing. This construction is well

known and need not be further described. It is such that at the proper time a stud g is pushed into the path of the tumbler to engage it and cause it to turn the shaft B so that the grippers will grip the paper and the stud g¹ is pushed into the path of the tumbler to cause it to turn the grippers to release the paper.

J is a stop which engages the tumbler and prevents it from being turned too far on the opening of the grippers.

The operation of the form of my invention described above is as follows: Fig. 1 shows in full lines the gripper, gripper tumbler and other parts in gripping position. The pin g has been thrown in to engage the gripper tumbler and cause it as it is carried by the cylinder (which moves in the direction of the arrow) to grip the paper sheet. It will be borne in mind that the cylinder rotates continuously. The sheet has been fed while the grippers are open over the feed board C² so that its front edge engages the front gages C¹. When the grippers have gripped a sheet the stud g is withdrawn and the cylinder rotates carrying the front edge of the sheet the desired distance, say about a complete revolution, when the stud g¹ is projected into the path of the tumbler and engages the corner d⁴ of the wall of the groove d¹ of the tumbler as the cylinder continues its rotation. This engagement of the tumbler causes its rotation to a sufficient extent to turn the grippers back, the groove allowing the tumbler to pass the stud. This is illustrated in dotted lines in Fig. 1. This rotation of the tumbler tends to compress the spring E and would put it to considerable strain except for the compensating action of the yoke lever F and cam surface d² upon which runs the roll f on the farther arm of the yoke lever F. Such stress is unnecessary, the only time when stress is needed being during the time when the spring must press the grippers against the paper. After its work is finished the stud g¹ is withdrawn and the cylinder keeps on its rotation until as it reaches the sheet-receiving position the stud g is projected into the path of the tumbler and engages it at the proper time, turning it and the grippers into gripping position. The tumbler thus takes the position shown in dotted lines in Fig. 1 and there remains until as the cylinder continues to rotate the tumbler strikes the pin g which has

been thrown in its path and causes it to turn again into the position shown in full lines in Fig. 1. The groove d³ in the tumbler serves to allow the pin g or g¹ to position the tumbler and at the same time allow the tumbler to pass the pin. The part of the cam with which the cam roll engages when the grippers are holding the sheet is concentric with the axis of the shaft, but the rest of the cam surface is shaped to allow the block e³, which serves as an abutment for the spring, to yield slightly as the pressure on the spring due to the rotating of the tumbler requires it.

In Fig. 2 there is a tumbler constructed as shown without a groove but connected with and controlled by a spring suitably mounted in so far as it bears at one end against what may be termed a floating abutment. The tumbler is lettered D¹ and its cam surface d²¹. It has a hub d¹⁰ by which it is attached to the shaft B from which it derives its motion. Its spring is lettered E¹ and it is mounted like the spring E about a rod having a shoulder e¹² against which one end of the spring rests, and means of pivotal attachment with the tumbler D¹ and also against a block e²¹ like the block e³ in the end of a slide F¹⁰. This slide F¹⁰ runs in a dove-tailed groove concentric with the cylinder in the bracket F¹¹ attached to the end of the cylinder and carries at the end opposite to that against which the spring bears a cam roll f¹⁰ which engages the cam surface d²¹. In this case as before a spring having a floating abutment serves to control the tumbler under substantially the same tension at all times, the cam surface serving to allow the floating abutment to yield when any unnecessary stress is given to the spring due to the turning of the tumbler.

I have shown two forms of my invention, but I do not mean to limit myself to these forms or to their precise arrangement. The floating abutment shown in Fig. 2 may be used with the tumbler shown in Fig. 1 and the floating abutment shown in Fig. 1 may be used at the farther end of the cylinder if thought best—without change other than would naturally occur to one skilled in the art.

What I claim as my invention is:—

1. In combination with a gripper shaft, a tumbler lever, a floating abutment and a spring one end of which engages said tumbler lever, the other end of said spring engaging said floating abutment, and means for controlling the movements of said abutment.

2. In combination with a gripper shaft, a tumbler lever, means for turning it, a floating abutment, and a spring one end of which engages said tumbler lever and the other said floating abutment, and means for

controlling the movements of said abutment to maintain said spring at substantially constant tension.

3. In combination with a gripper shaft, a tumbler lever, means for turning it, a floating abutment, and a spring one end of which engages said tumbler lever and the other said floating abutment, and means for controlling the movements of said abutment comprising a cam roll connected to said abutment and a cam located to control the movements of said cam roll.

4. In combination with a gripper shaft, a tumbler lever, means for turning it, a floating abutment, and a spring one end of which engages said tumbler lever and the other said floating abutment, and means for controlling the movements of said abutment

comprising a cam roll connected to said abutment and a cam located on said tumbler lever to be engaged by said cam roll.

5. In combination with a gripper shaft, a tumbler lever, means for turning it, a floating abutment, and a spring one end of which engages said tumbler lever and the other said floating abutment, and means for controlling the movements of said abutment comprising a movable support for said abutment carrying a cam roll, a cam located on said tumbler lever adapted to be engaged by said cam roll as and for the purposes set forth.

HARRY P. GUILLO.
